UNITED STATES PATENT OFFICE

WILBUR H. ARMACOST, OF NEW YORK, N. Y., ASSIGNOR TO THE SUPERHEATER COMPANY, OF NEW YORK, N. Y.

COMBINED SUPERHEATER AND BOILER

Application filed January 21, 1930. Serial No. 422,339.

My invention relates to the art of steam production and aims to provide an efficient arrangement of superheater and boiler adapted for economical manufacture, installation and operation.

In supplying superheated steam to prime movers from combined superheaters and boilers having common furnaces, difficulty has been experienced in maintaining the temperature variations of the superheated steam within desired limits at different rates of firing.

It is an object of my invention to provide a combined superheater and boiler adapted to avoid such difficulty.

In accordance with the aims above stated, a superheater boiler installation within my invention may comprise a superheater, boiler and furnace having the superheater elements arranged in two groups, one of which is so positioned with respect to the furnace and boiler that it receives a considerable portion of its heat by radiation from the furnace and the other group of elements arranged so that it receives the most of its heat from the combustion gases from the furnace and so that the percentage of surface area of the second group of superheater elements in the stream of combustion gases from the furnace increases with an increase in rate of firing of the furnace. Furthermore, the boiler is preferably connected to the two groups of superheater elements so that the saturated steam flows from the boiler into the group subjected to the greater amount of radiation and then into the group of elements receiving its heat primarily from the furnace gases, the two groups being in series in the path of the steam flow. It is a feature of my invention also to so arrange the group of superheater elements receiving the greater amount of radiation that the percentage of its surface area lying in the stream of combustion gases changes very little with ordinary changes in rate of firing of the furnace. In practical installations, it has been found desirable to place the convection group of superheater elements outside of the steam generating tubes and the radiant group of super-

heater elements intermediate the bank of generating tubes nearest the fire.

The novel features of my invention are pointed out with particularity in the appended claims. The invention, however, together with further objects and advantages, will best be understood from a detailed description of an illustrative arrangement of a combined superheater, boiler and furnace embodying the invention and such a description will now be given in connection with the accompanying drawings in which

Fig. 1 is a sectional elevation through a cross drum boiler having semi-vertical tubes combined with a superheater and furnace in accordance with my invention; Fig. 2 is an enlarged section on the line 2-2 of Fig. 1 looking in the direction of the arrows.

Referring to the drawings more in detail, the illustrative embodiment of my invention therein shown comprises a boiler having upper drums 10, 12, connected by water tubes to a lower drum 14, said tubes comprising a front bank 16 and rear banks 18 and 19. The front wall of the boiler setting is shown at 20 and below the drum 14 and tubes 16 is a furnace chamber 22. The bank of tubes 16 is shown in semi-vertical position and as inclined forwardly from the vertical to some extent in passing from the lower drum 14 to the upper drum 10, so that the upper end of bank 16 lies nearer the front wall 20 than the lower end and the upper drum 10 is in front of lower drum 14. A baffle 24 is shown at the rear of bank 16 running parallel to the tubes of such bank and arranged to direct the combustion gases from furnace 22, in large measure, longitudinally of the tubes in such bank.

In addition to the bank of tubes 16, drums 10 and 14 are shown as connected by a set of tubes 26 lying in front of the bank 16. At their point of exit from drum 14, tubes 26 are shown as running almost horizontally, but a short distance from drum 14 such tubes incline upwardly somewhat from the horizontal and extend forward nearly to the front wall 20. Near the front wall, tubes 26 curve upwardly and then re-curve toward the bank 16, running from near the front wall some-

what upwardly to a point 28 near the bank 16 and thence extending upwardly to the drum 10 parallel to such bank so as to leave a space 29 between their upper portions and wall 20.

5 The elements of the superheater are shown as divided into two groups, one of which is designated as 30 and lies within the space outlined by the tube bank 16 and the upper portions of tubes 26. Elements in group 10 30 run parallel to the tubes of bank 16 and are fastened to tubes of bank 16 and additional tubes 26 by straps 31, 31. Elements of group 30 extend downwardly toward the 15 furnace 22 so as to receive considerable heat by direct radiation from the furnace. Furthermore, elements of group 30 are so interspersed in the tubes of bank 16, and the bank 16 and baffle 24 are so arranged that the major 20 portion of the surface area of the elements of group 30 lies in the stream of combustion gases from furnace 22 even at low firing rates of the furnace, whereby the total of heat units imparted to the steam by the elements 25 of group 30 changes very little with ordinary changes in the rate of firing. A suitable arrangement of tubes 16 and 30 for such purposes is illustrated in detail in Fig. 2. As shown, the tubes in bank 16 and the additional tubes 26 are $3\frac{1}{4}$ " outside diameter and are spaced $6\frac{3}{4}$ " between centres both in the direction parallel to baffle 24 and in the direction at right angles to it. Tubes in group 30 may be either of $1\frac{5}{8}$ " or $1\frac{1}{2}$ " inside diameter when used with tubes 16 of the size and arrangement above stated and are arranged preferably parallel to tubes 16 in rows running at right angles to baffle 24 and spaced somewhat closer together within bank 16 35 than in the space between bank 16 and tubes 26 and between tubes 26. Each row of tubes 30 preferably contains four tubes in the space within tube bank 16 and two tubes outside such bank, one between bank 16 and tubes 26 and one within the space outlined by 40 tubes 26.

A second group 32 of superheater elements is shown in the space 29 intermediate the upper ends of the additional tubes 26 and the 45 front wall 20. Elements of group 32 are held together by transverse braces 34, 34, and the lower end of the front elements of such group are supported on an angle 35 fixed to the re-curved portion of the water tubes 26 while 50 the upper ends of the front elements of such group rest on angle 37 fixed to the front wall 20. It will be seen that the elements of group 32 are so placed that only a minor portion of their surface area lies in the stream 55 of combustion gases from furnace 22 at low firing rates of the furnace but that, as the rate of firing of the furnace is increased, the stream of gases is thereby widened to increase the portion of the area of such elements in 60 amount of contact with the gases of combus-

tion and thereby to increase the total heat delivered to the steam with increase in rate of steam generation. It will be evident also that the elements of group 32 receive a relatively small amount of heat by radiation from furnace 22 not only on account of their distance from the furnace but also on account of the relatively large amount of shielding from radiation afforded them by the re-curved portions of the additional tubes 26.

70 The groups of elements 30 and 32 are connected in series in the path of the steam flow and, in accordance with my invention, the group 30 receives the saturated steam direct from the boiler, thereby protecting group 30 80 against overheating. For this purpose, saturated steam is conducted from the rear drum 13 of the boiler through a steam pipe 36 to a header 38 to which the elements of group 30 are connected by the steam leads 40. The 85 other ends of the elements of group 30 are connected to a second header 42 by steam leads 44. From header 42 steam may be conducted to the superheater elements 32 by steam leads 46, the other ends of elements in group 32 being connected to a third header 48 by means of steam leads 50. From header 48 the steam may be conducted to the prime mover or other steam consuming apparatus 90 by means of a pipe 52.

95 If desired, additional water heating surface may be supplied by means of tubes 54 below the combustion zone and connected between a rear header 56 and a front header or drum 58, steam from drum 58 passing into 100 drum 10 through pipe 60.

A steam generating apparatus designed and operating on the principles above described is capable of supplying large quantities of steam at a high degree of superheat 105 but with relatively slight variations of superheat with changes in boiler rating. Moreover, the super-heater elements have a comparatively long life.

110 I claim:

1. The combination of a furnace, a boiler heated thereby, two groups of superheater elements, one of which is arranged to receive a relatively large amount of radiant heat from said furnace as compared to the other, 115 said other group of superheater elements so arranged with respect to said boiler and furnace that the percentage of its surface in the stream of combustion gases from the furnace increases automatically with increase in rate 120 of operation of the furnace, and connections leading steam from the boiler first through said radiant group of elements and then through said other group.

2. The combination of a furnace, a boiler heated thereby, two groups of superheater elements, one of which is arranged to receive a relatively large amount of heat from said furnace by radiation as compared to the other and to have the major portion of its 125 130

- surface within the gas stream at low rates of firing, said other group of superheater elements arranged to be heated primarily by contact with gases from said furnace and so arranged with respect to the boiler and furnace that the percentage of its surface in the stream of combustion gases increases automatically with increase in rate of operation of the furnace, and connections leading steam from the boiler directly to said radiant group and there to said other group of superheater elements.
3. The combination with a furnace, of a boiler having an inclined bank of water tubes arranged to receive radiant heat from said furnace at one end, a baffle arranged to direct the combustion gases along said tubes, a group of superheater elements extending parallel to said tubes into the zone of radiant heat and so interspersed among said water tubes as to restrict the volume of gases flowing through the space outlined by the tube bank and elements to prevent material variations in the amount of heat absorbed by such group with variations in rate of steam generation, a second group of superheater elements relatively sheltered from radiation and so arranged that the combustion gases from said furnace flow automatically over a greater percentage of its area with increasing rates of combustion, and connections for leading steam from said boiler through the elements of said groups.
4. The combination of a boiler comprising an upper drum, a lower drum, and a front bank of semi-vertical water tubes connecting said drums, a baffle extending upwardly from said lower drum along the rear of said bank, additional water tubes connecting said drums and extending forwardly from said lower drum, and then recurving toward said bank, a group of superheater elements interspersed in the tubes of said bank and running parallel therewith, a second group of superheater elements lying above the recurved portion of said additional tubes, and steam connections between said boiler and groups of elements.
5. A boiler as set forth in claim 4 together with means leading saturated steam directly from the boiler to the interspersed group of elements and from the interspersed group to the second group of elements.
6. The combination of a boiler having a lower drum, an upper drum in front of said lower one and a front group of water tubes connecting said drums, a group of superheater elements interspersed in said tubes, a second group of superheater elements in front of said tubes, and steam connections between said boiler and groups of elements.
7. The combination of a furnace, a boiler heated thereby and having a lower drum and an upper drum in front of said lower one, and water tubes connecting said drums, the front ones of said tubes running forwardly above the furnace and then recurving toward the others, a group of superheater elements interspersed in said tubes, a second group of superheater elements in front of the upper portions of said tubes and above the recurved portion of said front tubes, and steam connections between said boiler and groups of elements.
8. The combination as set forth in claim 6 and in which the steam connections lead the steam from the boiler directly to the group of superheater elements among the water tubes and then to the group in front of the water tubes.
9. The combination as set forth in claim 7 and in which the steam connections lead the steam from the boiler directly to the group of superheater elements among the water tubes and then to the superheater elements in front of the water tubes.
10. The combination as set forth in claim 6 and in which the water tubes are so arranged with respect to the elements interspersed therein that the amount of gases contacting with the interspersed superheater elements varies relatively little compared with variations of boiler rating throughout the ordinary range of such variations.
11. The combination of a furnace, a boiler heated thereby, two groups of superheater elements both directly above said furnace, one of said groups being arranged to receive a relatively large amount of radiant heat from said furnace as compared to the other, said other group of superheater elements being so arranged with respect to said boiler and furnace that the percentage of its surface in the stream of combustion gases from the furnace increases automatically with increase in rate of operation of the furnace, and connections leading steam from the boiler first through said radiant group of elements and then through said other group.
12. The combination of a furnace, a boiler heated thereby and having an up-pass for gases from said furnace, two groups of superheater elements both in said up-pass, one of said groups being arranged to receive a relatively large amount of radiant heat from said furnace as compared to the other, said other group of superheater elements so arranged with respect to said boiler and furnace that the percentage of its surface in the stream of combustion gases from the furnace increases automatically with increase in rate of operation of the furnace, and connections for leading steam from the boiler first through said radiant group of elements and then through said other group.
13. The combination as set forth in claim 12 and in which the radiant group of elements is interspersed among tubes of the boiler and the convection group of elements lies outside the space outlined by the boiler tubes.
14. The combination with a furnace, of a

- boiler having an inclined bank of water tubes arranged to receive radiant heat from said furnace at one end, a baffle arranged to direct the combustion gases along said tubes,

5 a group of superheater elements extending parallel to said tubes into the zone of radiant heat and so interspersed among said water tubes, as to restrict the volume of gases flowing through the space outlined by the tube,

10 bank and elements to prevent material variations in the amount of heat absorbed by such group with variations in rate of steam generation, a second group of superheater elements arranged at substantially the same distance

15 from the furnace as a portion of said first group, but relatively sheltered from radiation and so arranged that the combustion gases from said furnace flow automatically over a greater percentage of its area with increasing rates of combustion, and connections

20 for leading steam from said boiler through the elements of said groups.

WILBUR H. ARMACOST.
